UNITED STATES PATENT OFFICE.

WALTER R. TOBLER, OF NEW YORK, N. Y., ASSIGNOR TO TOBLER & HOENIG, OF NEW YORK, N. Y., A FIRM COMPOSED OF FRANZ HOENIG AND WALTER R. TOBLER.

DESIGN FOR EMBROIDERY, LACE, OR ARTICLE OF SIMILAR NATURE.

Application filed August 26, 1922. Serial No. 3,569. Term of patent 3½ years.

To all whom it may concern:

Be it known that I, WALTER R. TOBLER, a citizen of Switzerland, residing at New York city, in the county and State of New York, have invented a new, original, and ornamental Design for Embroidery, Lace, or Article of Similar Nature, of which the following is a specification, reference being had to the accompanying drawing, forming a part thereof.

The figure is a portion of a piece of embroidery showing my new design.

What I claim as new is:

The ornamental design for embroidery, lace, or article of similar nature, as shown.

WALTER R. TOBLER.
